UNITED STATES PATENT OFFICE.

WILBUR L. MERRILL, OF SCHENECTADY, NEW YORK, ASSIGNOR TO GENERAL ELECTRIC COMPANY, A CORPORATION OF NEW YORK.

CONTROL OF DYNAMO-ELECTRIC MACHINES.

Application filed November 7, 1922. Serial No. 599,576.

To all whom it may concern:

Be it known that I, WILBUR L. MERRILL, a citizen of the United States, residing at Schenectady, county of Schenectady, State 5 of New York, have invented certain new and useful Improvements in the Control of Dynamo-Electric Machines, of which the following is a specification.

The object of my invention is to provide 10 a system for controlling the torque of electric motors employed in power systems, and in particular to a system for controlling the tension on a cable or the like which connects two objects between which there is a relative 15 motion.

Although the invention is not necessarily limited thereto, it has a particular application in equipments for towing one object by another relatively movable object, such, for 20 example, as towing one ship by another, and also in equipments for warping or mooring a ship to a dock.

Due to the undulating movement of the water, the tow line between two ships, or 25 the mooring line between a dock and a ship, is subjected to stresses which are continually varying. As long as the undulating movement is relatively small, the variations in stress in the towing or mooring line will be 30 taken up in the catenary of the line, but for conditions such as experienced in a heavy sea, the catenary of the line can not be relied upon to compensate for variations in the 35 distance between the objects connected by the line.

One of the objects of the invention is to provide an improved arrangement for automatically compensating for all variations in 40 the distance separating two objects which are connected by means of a cable, line, chain, or the like, so that the stress set up may be within the limits of safe operation.

A further object is to provide means 45 whereby the cable, line, or other connecting device, may be let out or taken in at will so as to initially connect the two objects, the distance between which is apt to vary.

Another object is to provide means whereby the torque of the towing or mooring machine may be adjusted at will so as to accommodate for different sizes of tows and 50 for various conditions of navigation.

In case the conditions are otherwise normal and the wind or sea strikes the tow 55 upon its side, the tow begins to yaw and the

tension of the cable is materially increased. Under these conditions it is impossible to stop this action by increasing the pull on the cable. Another object of the invention is to provide an arrangement whereby under such 60 conditions the pull on the cable will be temporarily decreased so as to allow the effective cable length to increase and increase the torque as the cable is paid out until such time as the pull on the cable will start the 65 tow properly following the ship by which it is being towed, and then automatically further increase the torque so as to pull the tow back to the original length of cable.

These and other objects of the invention 70 as will either be apparent to those skilled in the art or as will be explained fully herein-after are attained in the system of control for dynamo electric machines which is shown 75 in very simple diagram in the accompanying drawing.

Referring to the drawing, Fig. 1 illustrates in very simple diagram a system of 80 motor control embodying the invention; Fig. 2 represents the various relations between the length of cable and the pull of the cable which may be obtained by the adjustment of the rheostat R^1 of Fig. 1; Fig. 3 represents the relations between the length of cable and the cable pull for various settings of the rheostats R^1 , R^2 and R^3 of Fig. 1; and Fig. 4 represents the conditions 85 which may be obtained for decreasing the pull of the cable when the towed ship begins to yaw.

Referring to Fig. 1, the cable or other device 10 which connects the ship (not shown) which is being towed with the ship (not shown) by which it is towed, has one end connected with the drum 11 so as to be wound thereon to vary the length of the cable. The apparatus which I shall now describe is preferably located on the ship which is doing the towing, although that is not necessary, since the apparatus could be located on the ship which is being towed. The electric motors 12 and 13 are connected 95 mechanically to the drum 11 by the gearing shown so as to normally set up a torque which opposes the tension or pull of the cable. These motors are preferably of the series wound type, although they need not necessarily be of this type. The current supply for these motors is provided by 100 the generator 14 which may be 110

driven in any suitable manner by any device, such for example as a steam engine or the like (not shown). The generator 14 is shown as of the separately excited type 5 having a shunt field winding 15 which is supplied from an excitation bus 16, and the generator and motors form together a type of Ward-Leonard drive. It is to be noted that while I have shown two electric motors 10 12 and 13 for setting up a torque in opposition to the pull of the cable 10, my invention is not necessarily limited to such an arrangement, since a single motor may serve the purpose. However, on shipboard where 15 space is a limiting factor, it may be desirable to provide two small motors as shown in order that the drum, the gearing and the motors may be confined within a limited space.

12 The control of the motors 12 and 13 is effected preferably by an arrangement which I shall now describe which varies the excitation of the generator field 15 in accordance with the requirement, although the 20 torque of the motors may be varied in other ways as will be understood by those skilled in the art. The variable rheostat R^1 is provided for adjusting the excitation of the generator field 15 and thus the voltage delivered by the generator 14, so that the current which traverses the motor circuits will 25 set up a torque which will practically balance the pull of the cable for a particular load on the cable. Thus, for example, if a 30 comparatively light ship is being towed, the greater part of the rheostat R^1 will be included in the generator field circuit, but if a heavy ship is being towed, a greater amount of this rheostat will be cut out so as 35 to thereby increase the torque set up by the electric motors 12 and 13. In Fig. 2 I have indicated by a number of horizontal lines the various values of torque which may be delivered by the electric motors to balance 40 the pull of the cable by various settings of the rheostat R^1 . It will be understood that provided the other field controlling rheostats are not varied and the rheostat R^1 is set for a particular cable pull, if the effective 45 length of cable which connects the two ships either increases or decreases, the torque of the motors 12 and 13 will remain substantially constant, as indicated in Fig. 2. Provision is thus made for adjusting the towing 50 equipment for various sizes of tows. It is desirable for the ordinary conditions encountered in towing one vessel by another that the pull on the cable set up by the torque of the electric motors 12 and 13 shall 55 increase gradually as the cable is paid out from the drum 11 and gradually decrease as the cable is wound upon the drum. Such a condition is encountered when the conditions of navigation are such that the distance 60 between the two ships is constantly 65 varying due to the undulating movements of the sea. By adjusting the rheostat R^1 to approximately a particular value of torque as explained in connection with Fig. 2, and adjusting the rheostat R^4 so as to exactly 70 cause the cable pull to be the desired value for a particular length of cable, the cable pull may be automatically increased as the length of cable increases, and automatically decreased as the length of cable decreases by 75 means of the automatically operated rheostat R^3 . This rheostat is arranged to be automatically operated in response to the forward and reverse movements of the electric motor 12 and thus in response to the 80 paying out and taking up of the cable, and in response to the tension or pull of the cable. The pull on the cable will thus be varied as indicated in dotted line, Fig. 3, for a particular setting of the rheostats R^1 85 and R^4 . It will be observed that the rheostat R^3 serves as a vernier for the rheostat R^4 . When the movable member 17 of the rheostat R^3 is in its upper position, the effective resistance of the rheostats R^3 and R^4 90 is the greatest, and when the movable member 17 is in the lowest position, the rheostat R^4 is short circuited.

95 In order to provide for automatically decreasing the pull of the cable when the towed ship begins to yaw I have provided what I shall term a "string" relay 18. This relay comprises a contact member 19 which cooperates with the contacts 20 so as to short circuit the rheostat R^2 in one position and with the stops 21 for limiting the movement of the member 19 in the opposite direction. The contact element 19 is mounted on the string 22 and the ends of the string are connected by means of the take-up spring 23. The string 22 passes over the sheave 24 which is held stationary, and also over the sheave 25 which is connected to rotate with the electric motor 12. The full line arrows 100 indicate the relative movements of the cable, drum, electric motor, rheostat element 17 and contact member 19 of the string relay when the pull of the cable predominates over the torque set up by the motors 12 and 13. The parts will be arranged so that ordinarily 105 the torque of the electric motors will slightly predominate over the pull of the cable for ordinary conditions, so that normally the motors have the tendency to take up the cable rather than pay out the cable. 110 This condition is indicated by the dotted line arrows and it is to be understood that the motors have such a torque under normal conditions that they merely have a tendency 115 as indicated by the dotted line arrows. This 120 tendency will be such that the torque of the motors merely predominates slightly over the pull of the cable but the tendency is not of such a value that the cable is constantly 125 being taken in. It will be observed that in 130

ordinary conditions the contact member 19 will make engagement with the contacts 20 and thus short circuit the rheostat R^2 , causing the pull of the cable to follow the line 26 of Fig. 4, as explained in connection with Fig. 3. When the pull of the cable predominates over the torque of the motors 12 and 13, the string relay 18 will be operated so as to break engagement with the contacts 20 and thereby introduce the resistance of the rheostat R^2 in the field circuit of the motor, causing the pull curve of the cable to follow the line 27, Fig. 4. The pull of the cable is thus momentarily decreased when the towed ship begins to yaw and cable is paid out from the drum 11. This will in many cases cause the towed ship to right itself with respect to the ship by which it is being towed, and when this occurs the torque of the motors 12 and 13 will predominate over the tension of the cable and the string relay will be operated to short circuit the rheostat R^2 , thus increasing the pull of the cable to the value indicated by the line 26, Fig. 4.

The disconnecting switch 28 will be opened in case it is desired to pay out the cable so as to initially connect the cable to the ship being towed.

In accordance with the provisions of the patent statutes, I have described the principle of my invention, together with the apparatus which I now consider to represent the best embodiment thereof but I desire to have it understood that the apparatus is only illustrative and that the invention can be carried out by other means.

What I claim as new and desire to secure by Letters Patent of the United States, is,—

1. The combination in a system of control for regulating the tension and the effective length of a cable or the like, of a dynamo electric machine mechanically connected to the cable to set up a torque in opposition to the pull of the cable, means for regulating the torque of said machine, and means operated in accordance with the movements of the machine for automatically governing the first mentioned means to initially reduce the torque of the machine when the pull of the cable predominates over the torque of the machine to permit the cable to be temporarily paid out and then gradually increase the torque of the machine as the effective length of the cable increases and decreases the torque of the machine as the effective length of the cable decreases.

2. The combination in a system of control for regulating the tension of a cable or the like, of a drum on which one end of the cable is wound, a dynamo electric machine mechanically connected to the drum to set up a torque in opposition to the pull of the cable, resistance for regulating the

torque of said machine, and means automatically operated in response to the paying out and taking in of the cable for regulating the said resistance to reduce the torque of said machine when the pull of said cable overcomes the torque of the machine to permit the cable to be paid out temporarily and then increase the torque of the machine as the cable is paid out.

3. The combination in a system of control for regulating the tension of a cable or the like, of a dynamo electric machine mechanically connected to the cable to set up a torque in opposition to the pull of the cable, a rheostat for regulating the torque of said machine, and means for automatically operating the said rheostat to reduce the torque of the machine when the tension of the cable overcomes the torque of the machine and to then increase the torque of the machine an interval after the tension of the cable is reduced.

4. The combination in a system of control for regulating the effective length and tension of a cable or the like, of a drum to which one end of the cable is connected, a dynamo electric machine mechanically connected to the drum, a rheostat connected to be operated in accordance with the operation of the machine for increasing the torque of the machine as the cable is paid out and decreasing the torque thereof as the cable is taken in, and another rheostat connected to be operated in accordance with the initial movement of the machine when the pull of the cable overcomes the torque of the machine for decreasing the torque of the machine to permit the cable to be paid out.

5. The combination in a system of control for regulating the tension of a cable or the like, of a drum to which one end of the cable is connected, a dynamo electric machine mechanically connected to the drum, a generator connected to supply current to the said machine to provide a torque for governing the length and tension of the cable, a separately excited field for said generator, a rheostat in the circuit of said field for determining the normal torque of the said machine, a second rheostat operated responsively to the taking up and paying out of said cable for increasing the torque of said machine as the cable is paid out and decreasing the torque thereof as the cable is taken up, and a third rheostat in the circuit of said field connected to be operated in response to the initial movement of said machine when the pull of the cable predominates over the torque of the machine for materially reducing the torque of the machine to permit the cable to be paid out.

In witness whereof, I have hereunto set my hand this 6th day of November, 1922.

WILBUR L. MERRILL.
